[57] **CLAIM**

The ornamental design for an enclosure for a telephone jumper-wire interface unit, substantially as shown and described.

DESCRIPTION

FIG. 1 is a perspective view of an enclosure for a telephone jumper-wire interface unit showing our new design;

FIG. 2 is a side elevational view of the form shown in FIG. 1, the opposite side being substantially similar in form;

FIG. 3 is an end elevational view of the form shown in FIG. 1, the opposite end being substantially similar in form; and

FIG. 4 is a top plan view of the form shown in FIG. 1.
